UNITED STATES PATENT OFFICE.

ALPHEUS G. LYNE, OF WASHINGTON, DISTRICT OF COLUMBIA.

FENCE-MAKING MACHINE.

SPECIFICATION forming part of Letters Patent No. 300,094, dated June 10, 1884.

Application filed December 18, 1883. (No model.)

To all whom it may concern:

Be it known that I, ALPHEUS G. LYNE, of Washington, in the District of Columbia, have invented a new and useful Improvement in Machines for Making Combined Wire and Picket Fences, of which the following is a full, clear, and exact description, reference being had to the annexed drawings, forming part of this specification.

10 This invention relates to machines for twisting two-strand cables of wire about fence-pickets to form a web of combined wire and picket fence, which can be wound upon spools convenient for shipment, and, when unwound, 15 can be rapidly stretched and secured to posts set in the ground.

Heretofore machines for making such a fence have been provided with rotary or oscillatory twisting devices, in each of which the two 20 strands of a cable are separately secured, and the pickets are fed in endwise between the strands as the intermittent action of twisting the latter proceeds. The object of my invention is to provide a machine, to be driven either 25 by hand or power, in which the pickets may be fed in between the strands laterally instead of endwise, with a view to securing a convenient and rapid working of the machine by one man, and at the same time to produce 30 a fence in which the wires shall be tightly twisted about the pickets so that they cannot readily become displaced or the pickets be withdrawn. This machine, while being adapted for making any kind of fence of the class 35 above described, has particular reference to the manufacture of a fence for which I have made application for Letters Patent, No. 106,913, filed September 20, 1883, in which differently-shaped pickets are arranged in alternate order, to prevent them from being displaced in the wires from any cause, and thus 40 to adapt the fence for turning all kinds of stock, especially hogs and cattle.

In carrying my invention into effect I provide 45 a series of rotary or oscillatory twist-ers, in each of which one of the strands of a cable is secured, while the other strand is carried by a rocking or movable frame, which is adapted to place the strand in the proper 50 twister, to be twisted together with the first named, and to remove it therefrom after the operation of twisting, to allow a picket to be fed in between the strands preparatory to the

next act of twisting. One-half of the strands of the several cables are thus parted from the 55 twisters simultaneously, and are likewise returned to the same, sufficient time being given for placing a picket in the machine in the meantime, which can be done by the operator with but little change of position, and need not require more than a few seconds. By thus parting the strands to admit the picket an important advantage is gained over the ordinary method, in that the picket can be placed close up in the 60 crotches against the twisted portion of the cables, causing the strands, when bent about the picket, to clasp it snugly on all sides, and thus preventing gaps in the wires, in which the picket may become loose. Another important feature of my invention is the means employed 70 for winding the completed web on the spool as it comes from the loom. For this purpose I employ a weight which is connected to a pivoted lever carrying a pawl for operating the spool-shaft by means of a ratchet-wheel 75 secured to the shaft. The lever is connected to the rocking frame above mentioned, by which it is repeatedly lifted to a position for allowing the weight to act upon the spooling mechanism, whenever the web of the fence 80 becomes slack by its increase of length. In this manner the winding of the fence on the spool, instead of being controlled by a calculated movement, which is difficult of proper 85 adjustment, is made solely dependent upon the growth of the web, so that the latter is wound with a uniform tension which is not affected by the gradual increase of the diameter of the spool, and which contributes to the 90 perfect working of the loom.

Having thus indicated the leading features of my invention, I will now proceed to describe the several parts in detail, and will afterward point out more particularly in the claims what I consider to be new in view of the state of 95 the art.

In the drawings, Figure 1 is a front elevation of the fence-machine as adapted to be worked by hand. Fig. 2 is a longitudinal section of the same on line x x of Fig. 1. Fig. 3 100 is a plan view of the machine as adapted to be run by power. Fig. 4 is a perspective view of the same. Fig. 5 is a detail view of part of the fence-spooling mechanism. Fig. 6 is a transverse section of the twisters and their 105 supports. Fig. 7 is an inverted plan view of

the picket-holding slide as adapted for the hand-machine. Fig. 8 is the fence-spooling shaft, showing the means for attaching the web thereto, the same consisting of two socket-pieces, one of which is shown as partly broken away and the other as removed from the shaft. Fig. 9 is a side elevation of part of the machine, showing the picket-feeding device. Fig. 10 is a partial front view of the said device, and Fig. 11 is a detached view of one of the tensioning devices.

A indicates any suitable frame-work, in the front beam, B, of which are journaled the series of twisters C. The twisters are formed with short cylindrical bodies D, on which they rotate, and have collars E at their inner ends and gear-wheels F at their outer ends, by which they are held from longitudinal movement. Through the wheel and body of each twister, near its periphery, is formed a longitudinal perforation, G, for holding one of the strands of a cable, and at an opposite point in the periphery of the same, and parallel with the perforation, is a groove, H, which registers with one of the spaces between the teeth of the wheel F, for receiving the other strand of the cable. The bearings of the twisters are so constructed that a vertical V-shaped or bevel slot, I, shall be formed between the ends of the box-caps J, with which the groove H will register when the twister is properly adjusted, to allow the removable strand to be passed in and out of engagement with the twister. The several twisters may be geared directly together, as shown in Fig. 1, or they may be connected together by intermediate gear-wheels, K, supported on shafts L, having collars M at their inner ends, as shown in Figs. 3 and 4.

A spool, N, of wire is mounted upon a shaft, O, supported in brackets P, attached to the side of each wheel F, in position for allowing the wire on the spool to be readily drawn through the perforation G to the rear of the machine; and each spool is provided with a tensioning device, Q, consisting of a lug which is to be attached to the wheel F at one side of the perforation G, and a clamping-plate arranged on the opposite side of the perforation, and connected to the said lug by set-screws, as shown in Fig. 11. In Fig. 4 I have shown a flat spring, q, adapted to bear against one end of the spool as a tensioning device, and various other well-known expedients may be used.

In the side beams, S T, of the frame-work is supported the movable frame U, which is adapted to rock on trunnions V, journaled in boxes W. This frame U is provided with a series of arms, X, having slots in their ends, and corresponding in number and position with the twisters C. On this frame are supported spools, Y, of wire, from which the wires are drawn off through slots Z in the ends of the said arms to the rear of the machine. These arms are provided with tensioning devices A', consisting of a block cut out from

the end of each arm at one side thereof, and provided with a screw by which it is clamped to the arm to bind the wire in the slot Z, as shown in Figs. 1 and 2. Instead of these, flat springs q, bearing against one end of the spools, as shown in Fig. 4, or any other suitable device may be used. The arms X are of such shape and length that when the frame U is moved down to the position shown in Fig. 2 their ends will be in alignment with the axes of the twisters, and the wires on the spools Y will be placed in the grooves in the twisters and held in a position to allow the latter to rotate without disarranging the wires in the arms. The trunnions V are to be so located with respect to the twisters that the arc described by the end of any arm X shall, as nearly as possible, coincide with an imaginary arc whose radius is represented by that part of the removable wire carried by said arm, which is comprehend between the end of the arm and the last twist of the wire, so that the several removable wires shall be held taut to facilitate their proper entrance into the grooves of the twisters.

While preferring a rocking carrier for the removable wires, I may use any movable device adapted to place the wires in and out of engagement with the twisters; and, instead of supporting the spools Y on the rocking carrier, they may be supported on a stationary supplemental frame, with their wires arranged in engagement with the carrier-arms.

When the rocking frame U is raised to the position shown in dotted lines in Fig. 2, a picket, B', is to be passed laterally over the twisters and placed upon the supports C' behind the fingers of the slide D'. The frame U is then to be moved down to the position shown in full lines in Fig. 2, placing the removable wires in the twisters, which latter are then to be rotated by suitable mechanism to twist the wires about the picket. By means of mechanism yet to be explained, the slide D' is to be moved back from the twisters to press the picket back as the rocking frame descends, and to hold it firmly in the crotches of the wires during the act of twisting. As the web E' increases in length it will be wound automatically upon the spooling-shaft F', in the manner hereinafter described.

In the drawings I have shown the machine adapted to be run either by hand or power. It is obvious that various arrangements of well-known expedients might be employed for operating the twisters, according as an oscillatory or a rotary movement in one direction is desired. As the twisters require a practically exact movement to cause the grooves H to register with the slots I at the end of their movement, it is important that there shall be as little lost motion as possible between them, and that a suitable stop-motion shall be employed.

In the hand-machine which is illustrated in Figs. 1 and 2, I have shown five twisters geared directly together, and a hand-wheel,

A², supported underneath the twisters and geared with the central one of the train. It is obvious that where the twisters are geared directly with each other, the grooves H in the 5 series will not all have exactly the same relative position; but this slight deviation is practically unimportant in the working of the machine. The wheel A² is designed to be of such relative size that one revolution thereof will 10 produce the required number of revolutions in the twisters for forming a twist in the cables, and it is provided with a stop consisting of a lug, B², attached to the side of the wheel, and a pin, C², set in the front beam of the 15 frame-work. With this construction the wheel is to be turned by hand, first in one direction and then in the other, until the lug strikes the pin. The wheel should be provided with one or two extra teeth, according to the thickness 20 of the lug and pin, to compensate for the space taken up in its periphery by said stop.

The wheel A² may be provided with counter-weights, or with a treadle; and instead of the wheel a toothed segment, sprocket-chain, 25 or rack-bar may be used, the said devices to be arranged underneath the twisters in an obvious manner, and operated by any suitable means. A rack-bar might be arranged in a vertical position at one end of the train and operated 30 by a treadle.

In the power-machine illustrated in Figs. 3 and 4, to secure a stop-motion for the twisters where the driving-shaft has a continuous motion in one direction, I employ a mutilated 35 gear, which a corresponding gear is adapted to lock once in every revolution thereof. This mutilated gear, (shown at A'), which should be of such a diameter that one revolution thereof will communicate the proper number of revolutions 40 to the twisters to form a suitable twist in the cables, is mounted upon the outer end of a shaft, B', journaled in the beams B C', and its motion is communicated to the twisters by the following convenient system of gears: 45 A gear-wheel, D', is mounted on the inner end of shaft B', and meshes with a pinion, E', preferably one-third the diameter thereof, mounted on the inner end of a shaft, F', arranged parallel with shaft B', and having on its outer end a 50 gear-wheel, G', which is of the same diameter as the twisters, and meshes with one of the same. With this construction, one revolution of wheel A' will make three revolutions of the twisters. The gear-wheel H', which locks 55 the mutilated gear A', is of a well-known description, having a portion, I', of its periphery formed without teeth, while the remaining portion is provided with the same number of teeth as the wheel A' contains. The teeth in 60 wheel H' will thus cause one revolution of wheel A', whereupon the portion I' of its periphery will be turned into the space J' of the mutilated gear, and fitting closely in the same between the ends of the series of teeth will 65 prevent the said gear from turning farther until the portion I' has passed and the teeth of the two wheels again mesh with each other.

To insure the proper meshing of said teeth at the start, the wheel H' is provided with a lug, K', which is adapted to strike a pin, L', on the 70 side of wheel A', to advance the latter to a position in which its first tooth will be engaged by the first tooth of wheel A'.

I prefer to form the wheel H' of such a relative diameter that its portion I' shall occupy 75 one-half its periphery, and provide the inner end of its shaft M', which is journaled in the beams B C', with a mutilated bevel-gear, P', the toothed portion of which, occupying one-half of its periphery, shall correspond in position 80 with the portion I' of wheel H', in order that said gear P' may be made to operate upon another part of the machine while the twisters are at rest. At right angles to the shaft M', and arranged under the side beams, S T, is a 85 shaft, Q', which is journaled in suitable bearings, and is provided with an unmutilated bevel-gear, R', of one-half the diameter of the gear P', and adapted to be engaged and rotated one revolution by the latter in a half- 90 revolution thereof. To the shaft Q' are secured two eccentrics, S' T', which are connected, respectively, to the sides of the rocking frame U below the trunnions V, in such manner that the frame U will be moved up to the 95 position shown in Fig. 4, and then down to the position shown in Fig. 3, at one revolution of the eccentrics. With this construction, the steady, continuous rotation of shaft M' by means of the band-pulley O' will operate the rocking frame and the twisters in 100 turn. The rods U', connecting the eccentrics with the frame U, may be slotted in a well-known manner at their connections with the latter, to allow the frame U to pause a moment when it reaches the position shown in Fig. 4, to give more time for placing a picket in the machine, if desired.

To the shaft Q' are also secured two eccentrics, V' W', arranged in the same relative 110 position as the eccentrics S' T', and having connecting-rods X', which are to be pivoted to suitable lugs on the under side of the slide D', for operating the latter. With this relative arrangement of the several eccentrics, the 115 slide will be moved forward when the rocking frame is raised, and as the latter descends the slide will be drawn back to press and hold the picket in the crotches of the wires. Each picket, in its turn, is thus drawn against the 120 twists of the cables, forcing the latter back from the twisters to make room for another twist. By thus using the picket for drawing the wires from the spools, the exact movement of the slide will cause the twists to be perfectly uniform, while the wires will be made 125 to embrace the picket closely on all sides, forming an even and compact web of fence. The web E⁴ is automatically wound on the spooling shaft F⁴ by the following means: To one 130 side of the frame-work at the rear of the machine is pivoted a lever, Y', which may be in the form of a flat bar, and is arranged above one end of the shaft F⁴ in such manner that it

may have a given downward sweep toward the shaft without coming in contact therewith. The lever is connected at its upper part to the lower part of one side of the rocking frame U by means of a chain or rope, Z', so that it will be lifted a given distance when the rocking frame is moved up to the position shown in Fig. 4.

To the upper end of the lever Y' is attached to a weight, D², which is adapted to draw the lever down when the rope Z' is slackened by the downward movement of the rocking frame. The lever is provided with a spring-pressed pawl, E², which engages with a ratchet-wheel, F², secured to the shaft F⁴, so that the downward movement of the lever will impart a corresponding movement to the ratchet-wheel and shaft, for taking up any slack in the web. A pawl, G², will prevent any backward movement of the ratchet-wheel. With this construction the weight D² is kept in a position for always acting on the spooling-shaft at the moment the web is pressed back by the feeding in of a picket. At other times the shaft 25 F⁴ is held by its pawl G², and the weight is supported by the rocking frame. The weight should be just sufficient to wind the web compactly on the shaft F⁴ without overcoming the action of the wire-tensioning devices at the front of the machine. A weight and lever may be arranged at each end of the shaft F⁴, if desired; or any other arrangement for equalizing the action of the weight on the shaft may be employed. Instead of the weight D², its equivalent—a spring—might be used. Such spring 35 may be a clock-spring, with which the shaft F⁴ may be removably connected in any obvious manner, and which spring, as it is allowed to uncoil and rotate the shaft, is constantly re-wound by a key connected to the rocking frame, or in other machines to any suitably-movable part.

The spooling-shaft F⁴ is provided with improved means for securing the web thereto, the same consisting of two sockets or holders for the ends of a picket. I prefer to secure one of these sockets or holders rigidly to the shaft, as at H², while the other, I², is made removable when the shaft is out of its bearings, 45 being formed, preferably, with a square opening, which fits over a square collar, J², on the shaft to prevent its turning thereon. With this construction, when the shaft is lifted out of its bearings, it can be readily withdrawn 55 from the roll of fencing thereon.

In the hand-machine the shaft Q² may be dispensed with and suitable longitudinal slots may be formed in the side beams, S T, in which a transverse shaft, K², is to be arranged. The 60 ends of this shaft are to project through the said beams and be connected to the sides of the rocking frame U below the trunnions V by means of connecting links or bars L², in such manner that the rocking of frame U will cause the shaft K² to move forward and backward in the slotted beams. This shaft is to be connected to the slide D' by means of slotted

links or bars M², as shown in Figs. 2 and 7. The slots in the links should be of such a length as to allow the shaft to give the exact movement to the slide that is required. In the hand-machine the rocking frame U may be provided with a weight, N², having a cord, O², which passes over a pulley, P², and is connected to the said frame above the trunnions V. This weight will act as a counter-weight to the weight D² of the fence-spooling mechanism, causing an easy and steady movement of the rocking frame when the latter is operated. Such counter-weights in the power-machine should be arranged to counterbalance the rocking frame against the twisters, so that the power shall pass evenly and smoothly from one to the other. Q² is a cross-rod connecting the arms of the rocking frame, which may serve as a handle for operating the said frame in the hand-machine.

In Figs. 9 and 10 I have shown a picket-feeding device for the power-machine. One side of the rocking frame U below the trunnion V is extended and formed into a segmental rack, R², which is adapted to pass under and engage a pinion, S², when the frame is rocked. This pinion is secured to a shaft, T², which is to be journaled in suitable bearings, U², attached to the front of the machine, and which is provided with curved arms V², adapted to receive a picket, and when moved up to the position shown in full lines in Fig. 9 to deposit the same behind the fingers of the slide D'. The ends of the arms V² are to be provided with holders for the picket, consisting of U-shaped projections formed of spring metal, into which holders the picket may be readily pressed; and the fingers of the slide D' are to have projections, as shown in dotted lines, adapted to overlap the upper side of the picket when the slide is pressed back, and to hold the same while the arms V² are being withdrawn.

What I claim is—

1. A wire-twister consisting of a smooth cylindrical body, on which it is adapted to rotate, having a longitudinal perforation near its periphery for holding one wire at a given distance from its center, and a longitudinal groove in its periphery opposite to the perforation for receiving and holding a removable wire at an equal distance from its center, substantially as shown and described.

2. A wire-twister consisting of a cylindrical body having a longitudinal perforation for holding one wire at a given distance from its center, and a longitudinal groove for receiving and holding a removable wire at an equal distance from its center, in combination with a bearing having an opening or slot with which the said groove may register, to receive the removable wire, substantially as shown and described.

3. A wire-twister consisting of a cylindrical body having a longitudinal perforation and groove therein, and means for holding a spool of wire on one end thereof, to allow the

wire to be passed through said perforation, in combination with means for passing a removable wire in and out of engagement with said groove, substantially as shown and described.

4. The combination of a suitable supporting-frame, a number of twisters having cylindrical bodies, on which they may rotate, each provided with means for holding one wire and preventing it from being moved radially from the twister, and means for holding the other wire and permitting it to be moved radially from the twister, means for gearing the several twisters together, a movable carrier for passing the removable wires in and out of engagement with the twisters, and tensioning devices for the wires, substantially as shown and described.

5. The combination of a number of twisters, each having a cylindrical body provided with means for holding one wire and preventing it from being moved radially from the twister, and means for holding another wire and permitting it to be moved radially from the twister, a supporting-frame having a slot or opening leading to each twister, means for gearing the several twisters together and for rotating or oscillating the same, a rocking frame for passing the removable wires in and out of engagement with the twisters, and tensioning devices for the wires, substantially as shown and described.

6. The combination of a number of twisters, each having means for holding one wire and preventing it from being moved radially from the twister, and means for holding another wire and permitting it to be moved radially from the twister, a supporting-frame, substantially as described, a rocking frame for passing the removable wires in and out of engagement with the twisters, and means for connecting the twisters and rocking frame together, whereby they may be operated in turn, substantially as specified.

45 7. The combination of a number of twisters, each having means for holding one wire and preventing it from being moved radially from the twister, and means for holding another wire and permitting it to be moved radially from the twister, a supporting-frame, a rocking frame for passing the removable wires in and out of engagement with the twisters, the mutilated gear A' and means for gearing it with the twisters, the gear H', adapted to lock the gear A', the shaft M', and mutilated gear P', the shaft Q', carrying the eccentrics S' T' and bevel-pinion R', and means for connecting the eccentrics with the rocking frame, substantially as shown and described.

55 8. The combination of the rocking frame, a transverse shaft connected to the said frame, and a transverse slide connected to the said shaft, substantially as and for the purpose set forth.

60 9. The combination of the twisters having passages for two series of wires, a series of

spools carried by the twisters, the wires of which spools are passed through the twisters, a series of spools supported above the machine, and a rocking frame adapted to place 70 the wires of said latter series of spools in and out of engagement with the twisters, and having tensioning devices for said wires, substantially as specified.

10. The rocking frame or lever for placing 75 the removable wires in and out of engagement with the twisters, in combination with the slide for pressing the pickets back into position for being secured in the wires, and means for connecting the slide with the said rocking frame, and the web-spooling mechanism having a lever for rotating the same, and means for connecting said lever with the rocking frame, substantially as and for the purpose specified.

11. The combination, with the rocking frame or lever, of the slide for pressing the pickets back into position for being secured in the wires, and means for connecting the slide with the said rocking frame, and the web-spooling 90 mechanism having a weighted lever, ratchet-wheel, and pawls, and means for connecting said weighted lever with the rocking frame, substantially as shown and described, whereby the two said functions of adjusting the pickets 95 and winding the web may be performed by operating the said rocking frame or lever, as set forth.

12. The combination, with the rocking frame or lever, of the web-spooling shaft having a 100 ratchet-wheel thereon and a retaining-pawl for the same, the weighted lever having a pawl for rotating said shaft, and the connection Z', connecting the weighted lever to the said rocking frame or lever below the pivot of the latter, substantially as and for the purpose set forth.

13. The fence-spooling shaft having a picket-holding device provided with a removable or adjustable socketed piece for receiving one 110 end of a picket, substantially as shown and described.

14. The fence-spooling shaft having a stationary collar provided with a socket for one end of a picket, and a removable collar having a socket for the opposite end of the picket, and means for preventing the latter collar from rotating on the shaft, substantially as shown and described.

15. The combination, with the rocking frame 120 having a segmental rack, of the picket-feeding device consisting of the oscillatory shaft having curved arms for holding a picket and a pinion adapted to be operated by the rack, and the slide having bent fingers adapted to 125 receive and hold the picket, substantially as shown and described.
